UNITED STATES PATENT OFFICE.

LEWIS ALLEN COHEN, OF HELENA, MONTANA.

GARMENT AND COVER SUPPORTER.

1,098,663.

Specification of Letters Patent.

Patented June 2, 1914.

Application filed August 16, 1913. Serial No. 785,175.

To all whom it may concern:

Be it known that I, LEWIS ALLEN COHEN, a citizen of the United States, residing at Helena, in the county of Lewis and Clark and State of Montana, have invented certain new and useful Improvements in Garment and Cover Supporters; and I do hereby declare the following to be a full, clear, and exact description of the invention, such as will enable others skilled in the art to which it appertains to make and use the same.

The present invention relates to covers or bags for protecting articles of clothing, and has for its purpose to provide a device of that character for use in connection with clothes hangers and which will effectively guard the contained garments against moths, dust, dampness, and exterior contact.

A further purpose of the invention is to provide a device of this character which readily permits of the insertion and removal of the garments without folding or creasing; and wherein the garment will hang without liability of ruffling or crushing.

With these and other objects in view the invention consists in the novel details of construction and combinations of parts more fully hereinafter disclosed and particularly pointed out in the claims.

Referring to the accompanying drawings forming a part of this specification in which like numerals designate like parts in all the views: Figure 1 is a front elevation of the device, and shows the same opened for inserting or removing the garment. Fig. 2 is a top plan view of the protector holder *per se*. Fig. 3 is a sectional view of the means for detachably connecting the holder members. Fig. 4 is a detail view showing the hinge connection between the movable bar and the supporting member. Fig. 5 is a front elevational view of a modified form of the invention; and Fig. 6 is a sectional view taken on the line *x-x* of Fig. 5.

Referring to the construction in further detail, the protector holder or supporting frame consists of a bar 1 providing a supporting member, and which is constructed to provide a suspending hook 2, and a supporting hook 3 for the hanger 4 of the garment A. A side member 5 is formed continuous with the supporting member 1, and at their points of connection said supporting and side bars are looped to provide a vertically disposed length or section 6 forming a hinge member for the coiled end 7 of

a second side bar 8 that is disposed opposite the side bar 5 with respect to the supporting member 1.

The bar 8 is adapted to have swinging movement on the supporting member 1, to the end that the protecting covering may be opened for the insertion and removal of the garment, as will be further explained. The two side bars 5 and 8 are adapted to have detachable connection with the supporting member 1 for applying and removing the protector covering and closing the same to infold the garment. To this end a plate 9 is mounted on the free end of the supporting member 1 and is provided with notches 10 and 11 to receive the free ends 12 and 13 of the side bars 5 and 8, respectively, after the manner illustrated in Figs. 2 and 3.

The protector covering consists of a fabric of any suitable material arranged into two folds 14 and 15, having their adjacent upper edges 16 and 17 piped to receive the side members 5 and 8 of the support, as shown in Fig. 1. The folds 14 and 15 are united along the side edge 18 by stitching or otherwise, and on the opposite side are adapted to be detachably connected through the medium of a number of French glove fasteners 19 arranged at suitable intervals.

The covering in its entirety is adapted to be readily applied and removed from the support, with the object that said covering may be removed when desired, and meanwhile another covering substituted in place thereof.

In the modified form illustrated in Figs. 5 and 6, the construction comprises a supporting member 20 formed of a metal strip adapted to be suspended by the hook 21, and having a hook 22 for supporting the garment hanger. A side bar 23 is formed as a continuation of the supporting member 20, and at their points of connection said bars 20 and 23 provide a hinge member 24 receiving the pin 25 on which is mounted to swing a second side bar 26 having the functions of the swinging bar 8 of the previous construction. The end of the supporting member 20 has welded or otherwise secured thereon an inverted U-shape member 27 providing a pair of hooks 28 and 29 adapted to receive the free ends of the side members 23 and 26, respectively. With this construction the side members 23 and 26 are adapted to have threaded or gathered thereon the piped edges of the fabric folds, as with the pro-

tector covering described above. And in this construction, likewise, said covering is adapted to be readily removed and replaced at will.

5 It is obvious that those skilled in the art may vary the details of construction and arrangement of parts without departing from the spirit of my invention, and therefore I do not wish to be limited to such features except as may be required by the claims.

I claim:

1. A holder for garment protectors comprising a member providing a support; a side member formed integrally with the supporting member and providing a hinge bearing; a second side member constructed with a coiled end hinged on said bearing and adapted to swing open; and a notched plate secured to the free end of said supporting member; both of said side members adapted

to have detachable engagement with said notched plate, substantially as described.

2. A holder for garment protectors comprising a bar providing a support and constructed with a suspension hook and a hook 25 for a hanger; a side bar formed continuous with said supporting bar, and the connecting portions of said bars providing a hinge bearing; a second side bar constructed with a coiled end hinged on said bearing and adapted to swing open; and the free ends of said side bars adapted to have detachable connection with the free end of said supporting bar, substantially as described.

In testimony whereof, I affix my signature 35 in presence of two witnesses.

LEWIS ALLEN COHEN.
